[57] CLAIM

The ornamental design for a combined watch and bracelet, as shown and described.

DESCRIPTION

FIG. 1 is a front elevational view of a combined watch and bracelet showing my new design;

FIG. 2 is a top plan view thereof, the bottom plan being a mirror image thereof;

FIG. 3 is a right side elevational view thereof;

FIG. 4 is a left side elevational view thereof;

FIG. 5 is a rear elevational view thereof;

FIG. 6 is a rear elevational view thereof with the band omitted for ease of illustration.

The dial center of FIG. 1 is lined for the color gold.

FIG. 4
FIG. 5
FIG. 6
